(57) **CLAIM**

We claim the ornamental design for a knife and sheath set, as shown and described.

DESCRIPTION

The patent or application file contains at least one drawing executed in color. Copies of this patent or patent application publication with color drawing(s) will be provided by the Office upon request and payment of the necessary fee.

FIG. 1 is a rear perspective view of a first embodiment of a knife and sheath set showing our new design;

FIG. 2 is a rear view thereof;

FIG. 3 is a left side view thereof;

FIG. 4 is a right side view thereof;

FIG. 5 is a front view thereof;

FIG. 6 is an enlarged top view thereof;

FIG. 7 is an enlarged bottom view thereof;

FIG. 8 is a rear perspective view of the knife and sheath set of FIGS. 1-7, now shown in shades of gray;

FIG. 9 is a rear view thereof;

FIG. 10 is a left side view thereof;

FIG. 11 is a right side view thereof;

FIG. 12 is a front view thereof;

FIG. 13 is an enlarged top view thereof;

FIG. 14 is an enlarged bottom view thereof;

FIG. 15 is a rear perspective view of a second embodiment of the knife and sheath set;

FIG. 16 is a rear view thereof;

FIG. 17 is a left side view thereof;

FIG. 18 is a right side view thereof;

FIG. 19 is a front view thereof;

(Continued)

FIG. 20 is an enlarged top view thereof; and, FIG. 21 is an enlarged bottom view thereof. The broken lines and the de-emphasized areas within them in FIGS. 6 and 13 depict portions of the knife and sheath set that form no part of the claimed design. The broken lines and the areas within them in FIGS. 15-21 depict portions of the knife and sheath set that form no part of the claimed design.

**1 Claim, 15 Drawing Sheets
(5 of 15 Drawing Sheet(s) Filed in Color)**
